UNITED STATES PATENT OFFICE.

MICHAEL F. BROGAN, OF LAWRENCE, MASSACHUSETTS, ASSIGNOR TO UNITED SHOE MACHINERY COMPANY, OF PATERSON, NEW JERSEY, A CORPORATION OF NEW JERSEY.

CEMENTING-MACHINE.

1,141,311.

Specification of Letters Patent.

Patented June 1, 1915.

Application filed August 28, 1907. Serial No. 390,481.

To all whom it may concern:

Be it known that I, MICHAEL F. BROGAN, a citizen of the United States, residing at Lawrence, in the county of Essex and Commonwealth of Massachusetts, have invented 5 certain Improvements in Cementing-Machines, of which the following description, in connection with the accompanying drawings, is a specification, like reference characters on the drawings indicating like parts in the several figures.

This invention relates to machines for applying cement or the like to stock and is illustrated in connection with a machine for 15 cementing soles, taps, or other pieces of stock.

In the manufacture of boots and shoes it is sometimes desirable to apply cement to one side only of a piece of stock and at other times to both sides.

20 One feature of the invention comprises a cementing machine having coöperating rolls, means for supplying cement to said rolls, and valves for selectively varying the amount of cement supplied to said rolls. With this 25 construction a desired amount of cement may be supplied to both rolls whereby cement is applied to both sides of the stock, or one valve may be closed so that cement is applied to one side only of the stock.

30 Another feature of the invention comprises a valve located in proximity to the cement applying roll and having a planed side past which the cement flows when said valve is open, the edge of the valve serving 35 to distribute the cement to the roll.

These and other features of the invention, including certain details of construction and combinations of parts will be explained in the following description and pointed out 40 in the claims.

Figure 1 is a side elevation of a machine embodying the invention in the best form now known to me; Fig. 2 is a perspective view; Fig. 3 is an end view; Fig. 4 is a detail; Fig. 5 shows a sole having the shank skived; Fig. 6 shows a molded sole.

The frame 2 supports the driving shaft 4 provided with fast and loose pulleys and carrying the upper roll 5. A counter-shaft 50 6 is connected with shaft 4 by gearing and carries the lower roll 8 so that both rolls are positively driven. Cement is supplied to the upper roll from a tank 10 carried on brackets 12, as shown in Fig. 3, and having a central depending portion with downwardly

inclined side walls in the base of which is formed an outlet in which is mounted a controlling device 15. This device comprises a shaft, the end portions of which are cylindrical, as shown in Fig. 4, to turn in bearings in the tank. The portions intermediate the end portions and which are located in the discharge opening are cut away on a chord to form the plane face at 16. The discharge opening is so shaped with relation to the shaft that it is completely filled and closed except for the opening afforded by the cut-away portion when the shaft is positioned as shown in Fig. 3, and by turning the shaft more or less the width of the outlet may be varied to regulate the discharge of cement. A plate 17 fast on the shaft and having an arc shaped slot into which projects a fixed stud on the tank limits the movement of the shaft and indicates when the outlet is closed. The shaft stands substantially in contact with the periphery of the roll 5 and serves not only as a valve or device for controlling the delivery of cement but also as a distributing device for spreading the cement. 70 A scraper 18 is supported at the rear of the roll 5 to remove any foreign material that may have been picked up by the roll. The roll comprises a hub of suitable material by which it is rotatably secured to the shaft, 75 and a body portion or thick covering of soft rubber, the acting face of which is deeply corrugated, and preferably the corrugations are formed by alternate grooves and ribs extending at right angles to the direction of 80 rotary movement, the ribs having angular outer edges.

It is found in practice that a roll constructed as described will carry the amount of cement necessary for thickly coating the 95 sole preparatory to "laying" the sole or applying it to the shoe bottom. The cement serves both as a temporary securing means and also to exclude moisture from the connection between the sole and the portions of the shoe adjacent to it. This construction also has the advantage, because of its yielding character, that it will apply a suitable coating of cement to the entire surface of the sole the shank of which is skived at the 100 edges, as shown in Fig. 5, the relatively high portions sinking into the soft rubber and yet receiving their proper coating of cement which is carried in the grooves between the ribs on the roll. Another advantage due to 105 110

the use of the soft, corrugated cement-applying roll, and preferably a supporting roll 8 of similar formation is that a sole which has been molded to the shape of the shoe bottom, as, for example, to the shape shown in Fig. 6, can be cemented without disadvantageously affecting its shape.

As above suggested, the supporting roll 8 is formed like the upper roll 5 with a thick body portion of soft rubber into which the article being coated may be deeply embedded without the use of pressure that would straighten out a molded sole or that would prevent cement being properly applied to the high portions of the article. For further adapting the machine to accommodate articles differing in thickness or having irregular shapes the supporting roll together with its shaft, is arranged upon a yieldingly supported frame 20 which is pivotally connected to a rod 22 that is rigid with the frame of the machine. Arranged in operative relation to the roll are tables 24, 25, the latter of which has a ribbed surface as shown to receive the cement-coated soles. These tables are both mounted upon the yieldingly supported frame 20 so that they maintain a constant relation to the supporting roll as its frame yields up and down. The frame 20 rests at its rear end upon a spring 26 through which extends a stud 28 having a wing nut by which the normal position of the roll may be varied. Provision is made for supplying the supporting roll 8 with cement or other material which may or may not be like the cement or other material with which the upper roll is supplied. To this end a tank 30 is provided which is supported by the rod 22 and by a connection to a tube 32 with a cement delivering member 34 arranged lengthwise under the roll 8 and secured in definite relation to the frame 20 and to the periphery of the roll. The delivering member 34 is provided with a controlling device 35, like the device 15 before described. The relation of these devices to their rolls is disclosed in Fig. 3 in which portions are broken away for that purpose. By reason of the arrangement shown the supporting roll 8 may move automatically as the work

varies in thickness or be adjusted into different relations to the roll 5 without disturbing its connection with the parts which supply it with cement or varying in any way the delivery of cement to it or the application of cement to the stock. The tube 32 is provided with an elbow as shown in Fig. 3; and, through the under wall of said tube at said elbow, is threaded a drain-plug 37. It is thus possible to shut off from either roll the supply of cement and to drain the lower tank, if desired.

Scrapers 40 are provided at opposite ends of each roll to engage the edges of the periphery of the roll and wipe the cement away from the end of the roll.

Having explained the nature of this invention and described a construction embodying the same, I claim as new and desire to secure by Letters Patent of the United States:—

1. In a cementing machine, the combination with a cement reservoir and a cement applying roll, of a device for controlling the flow and distribution of cement arranged in close proximity to the roll and comprising a shaft having a planed side and adapted to be adjusted to permit the cement to flow past said planed side and to be distributed upon the roll by one edge thereof.

2. In a cementing machine, the combination with a cement applying roll and a supporting roll, and a yieldingly upheld frame pivoted at one side of the supporting roll and provided with bearings for said roll, of tables arranged at either side of said roll and supported by the frame whereby they are maintained in constant relation to the roll.

3. A cementing machine having, in combination, a roll, a coöperating roll, means for supplying cement to said rolls, and valves for selectively varying the amount of cement supplied to said rolls.

In testimony whereof I have signed my name to this specification in the presence of two subscribing witnesses.

MICHAEL F. BROGAN.
